UNITED STATES PATENT OFFICE.

CHARLES WILSON BEAMER, OF BURBANK, CALIFORNIA.

SANITARY CUSPIDOR.

Application filed July 15, 1924. Serial No. 726,219.

To all whom it may concern:

Be it known that I, CHARLES WILSON BEAMER, a citizen of the United States, residing at 615 Santa Anita Avenue, Burbank, in the county of Los Angeles and State of California, have invented a new and useful Sanitary Cuspidor, of which the following is a specification.

The present invention relates to a sanitary cuspidor, and aims to provide a device with means whereby the lid of the cuspidor may be quickly and conveniently flushed.

With the above and numerous other objects in view as will appear as the description proceeds, the invention resides in certain novel features of construction, and in the combination and arrangement of parts as will be hereinafter more fully described and claimed.

20 In the drawing:—

Figure 1 is a vertical longitudinal section through my improved structure.

Figure 2 is a horizontal section therethrough, taken substantially on the line 2—2 of Figure 1, looking downwardly, and

Figure 3 is a plan view of the sprayer.

Referring to the drawing in detail it will be seen that 5 designates a casing which is provided with an extension 6. A flange 7 extends inwardly from the upper edge of the casing 1, and closes the upper end of the extension 6. The inner edge of this flange is extended downwardly as is indicated at 8. The bottom end of the casing 35 is open, and a tank 9 is supported in the bottom portion of the casing, and is adapted to contain water which may have therein a solution of any suitable disinfectant. A cylinder 10 is extended into the tank 9

40 within the extension 6, and a plate 11 is threadedly engaged with the upper end thereof and rests on the upper wall of the tank 9. A stem 12 is slideable through the plate 11 into the cylinder 10 and a stuffing box 13 is arranged thereabout, being threadedly engaged with the plate 11. This stem 12 projects upwardly through the flange 7, and terminates in a head 14. A spring 15 is disposed about the stem 12 between the head 14, and the stuffing box 13, and normally holds the stem 12 in the raised position as shown in Figure 1. A plunger 16 is mounted on the end of the stem 12 within the cylinder 10. A check valve 17

is provided in the bottom of the cylinder 10, and allows the liquid to flow into the cylinder upon the upward stroke of the plunger and prevents the liquid in the cylinder from flowing therefrom upon the downward stroke of the plunger. Another 60 check valve 18 is mounted in the side of the cylinder 10 and operates oppositely from said valve 17. A sprayer is attached to the check valve 18 and includes the vertical tubular member 19 which is curved rectangularly at its upper end as is indicated at 20 and terminates in an annular perforated portion 21 disposed about the downwardly extending portion 8 of the flange 7. The cuspidor proper 22 is mounted on the upper 70 wall of the tank 9 and the conical shaped lid 23 thereof has its opening coaxially arranged with the opening in the flange 7 having the depending portion 8. The diameter of the lid 23 is greater than the diameter of the last mentioned opening.

From the above detailed description it will be seen that by pressing downwardly on the stem 12, the plunger 16 may be moved downwardly in the cylinder 10 so as to force 80 the contents of the cylinder out through the check valve 18, tubular member 19 and annular extension 21 for flushing the lid 23 of the cuspidor 22. The spring 15 will return the plunger to its raised position, at the same time drawing the contents of the tank 9 into the cylinder. It is further to be noted that the parts are capable of being easily assembled and disassembled.

Having thus described my invention, what I claim as new and desire to secure by Letters Patent is:—

In a device of the class described, a tank, a casing disposed over the tank, a cylinder in the tank, a plunger in the cylinder, means for operating the plunger, check valves associated with the cylinder, a tubular member extending from one of the check valves and terminating in an annular perforated portion, a casing disposed about the tank, a cuspidor rested on top of the tank within the casing, and including a lid, said casing provided in its upper wall with an opening having a depending portion at its edge about which extends the annular perforated portion.

CHARLES WILSON BEAMER.
